(57) **CLAIM**

The ornamental design for a slider valve fitment probe, as shown and described.

DESCRIPTION

FIG. 1 is a top perspective view of a slider valve fitment probe. FIG. 2 is a bottom perspective view of the slider valve fitment probe.

FIG. 3 is a side view of the slider valve fitment probe.

FIG. 4 is a front view of the slider valve fitment probe.

FIG. 5 is a top view of the slider valve fitment probe.

FIG. 6 is a bottom view of the slider valve fitment probe; and, FIG. 7 is a second top perspective view of the slider valve fitment probe, including environmental features.

The broken line showing in FIG. 3 is included for the purpose of illustrating portions of the article and forms no part of the claimed design. The broken line showing of the collar in FIG. 7 is included for the purpose of illustrating environmental structure and forms no part of the claimed design.
